CATCH NET FOR CHILDREN'S PLAY PENS

Norman C. Le Roy, Miami, Fla.

Application June 2, 1950, Serial No. 165,650

6 Claims. (Cl. 5—317)

1

This invention relates to a catch net for detachable and collapsible attachment to children's play pens.

An object of the present invention is to provide a net structure adapted to be extended entirely around the pen and to be angularly disposed from the side of the pen at a distance calculated to catch and entrap articles, such as bottles or toys that might be thrown or roll from the pen, with the net snugly engaging the bottom portion of the pen to prevent articles passing therebetween.

The invention contemplates novel support means for detachably mounting the net to the pen, which support means is swingably mounted at each corner of the pen to be manually shifted outwardly for disposing the net at an angle and with latch means for maintaining the supports in either the extended or retracted position, with the supports in the extended position maintaining the net relatively taut.

Another object of the invention resides in forming the net in a single piece and having its upper marginal edge provided with an elastic band whereby the net will be drawn together as the supports are shifted inwardly and with the lower marginal edge of the net provided with a draw string whereby the net may be held in snug engagement with the lower part of the pen against articles passing therewith.

Another object of the invention resides in the novel means for quickly and easily attaching the mounting and supporting rods for the net at each corner of the crib, being so constructed that they may be either attached with wood screws, or special clamp devices to engage the legs of the pen.

A further object of the invention resides in the extreme simplicity of the net structure and its supports and the ease with which it may be mounted upon a play pen, the invention containing few and simple parts that are cheap to manufacture, and will maintain the net in extended angular position against accidental collapsing, is quickly and easily released to collapsed position when an attendant wishes to administer to the pen occupant, and offers no projecting obstacle to a proper access to the pen, nor resistance to the passage of air therethrough.

Other and important objects of the invention will be readily apparent during the course of the following description, reference being had to the accompanying drawings wherein has been illustrated structures embodying the invention and wherein like characters of reference are employed to denote like parts throughout.

Referring to the drawings:

Figure 1 is a perspective view of a play pen showing the invention applied thereto.

Figure 2 is a fragmentary elevation of one corner of the play pen, showing one net positioning support in elevation and with the attached net in section.

Figure 3 is a fragmentary top plan view of one corner of the pen, with the invention applied thereto.

10 Figure 4 is a vertical section through the net support, taken on line 4—4 of Figure 3.

Figure 5 is a horizontal section through a leg of the pen, with a corner mounting member in fragmentary top elevation and illustrating a modified form of attaching means.

Figure 6 is a fragmentary perspective of a modified form of net support and,

Figure 7 is a section on line 7—7 of Figure 6.

Referring specifically to the drawings and particularly to Figures 1 to 4 inclusive, the numeral 5 designates a conventional play pen, generally square in top plan and having open sides 6, a bottom 7 and ground legs 8. The specific structure of the play pen is relatively unimportant, since the invention readily adapts itself to pens of varying forms.

Mounted at the corner legs of the pen and at the same elevation from the bottom of the legs, are angle brackets 9, secured to the legs 8, by screws 10, passing through openings 11 of the angles. The angles are further provided with slots 12, for a purpose to be presently described. Each angle at its apex, is provided with a relatively thick laterally extending ear 13, rounded at its forward end and provided with an opening 14.

35 The ears 13 are each adapted to pivotally support a bifurcated tubular head 15, terminating in an elongated axial tubular extension 16, open at its upper end. A pivot pin 17 pivotally supports the head 15 with respect to the ear 13. Since the member 16 and head 15 constitute a rigid swingable support, it has been found desirable to provide latch means for maintaining the support either in an angular or vertical position. For this purpose, the ears are provided with notches 18, for the reception of a latch dog 19, urged outwardly by a spring device 20. The latch dog is controlled by a rod 21, passing upwardly through the tube 16 and provided at its outer end with a spherical member 22, whereby the rod 21 may be drawn upwardly to release the dog 19. The tubes 16, adjacent their outer ends, are provided with fixed loops 23, to which are attached the upper marginal edge of the net 24. The upper marginal edge of the net is preferably provided with an

50 55

elastic cord, indicated at 25 in Figure 4. The elastic cord 25 maintains the upper edge of the net taut when in extended angular position and draws the net together when the supports are released to move inwardly to lie in substantial parallelism with the edge of the legs 8. Thus, the net will be bunched together and not sag downwardly when in the collapsed position. The lower marginal edge is preferably provided with a draw string, indicated generally at 26, through the medium of which the lower edges may snugly engage the sides of the pen entirely therearound in close proximity to the bottom of the pen 7, thus assuring that obstacles falling in the net will not roll downwardly and pass between the net and the bottom 7.

In the use of this form of the invention, the operator first attaches the angle brackets 9, carrying the supports, including the heads 15 and tubes 16. The several supports are released and swung inwardly to vertical position and latched. The upper marginal edge of the net 24 is then attached to each tube 16, through the medium of the loops 23. The lower marginal edge of the net is then drawn snugly around the pen to overlie the brackets and the cord 26 is drawn tight and tied. The several supports are then again released from their latching engagement with the ears 13 and swung outwardly to assume the predetermined angle shown and latched in position. An attendant wishing to have access to an occupant of the pen, merely releases one or more of the latches, through the medium of the spherical members 22, swinging the supports inwardly to their inner latched position, carrying with them the net 24. Thus the device is quickly and easily extended or collapsed as desired.

It has been found desirable in some instances, to employ clamps for attaching the angle brackets 9 to their respective legs 8. For this purpose, conforming straps 27 and 28, having hooked ends 29, are engaged within the slots 12 of the brackets and then folded or bent around the leg 8. The terminal ends of the straps are punched to provide aligned openings for the joint reception of bolts 30, through the medium of which the straps are drawn tightly to hug the legs, thus rigidly positioning the angle brackets 9 to the legs. The conforming straps 27 and 28 readily conform to the various leg dimensions, since manufacturers frequently vary their output.

A modified form of net support has been illustrated in Figures 6 and 7. In this form of the invention, the angle brackets 31 is employed, having screw openings 32 and slots 33. However, instead of the ears 13, U-shaped sockets 34 are employed. The sockets 34 may be formed integral with the brackets, or may be subsequently attached as by welding. The forward end of each socket is inclined outwardly at an angle corresponding to the desired angle of the support for the net 24. Pivotally supported within each socket, as by pivot pins 35, are tubular members 36, serving as tubular sockets for elongated support rods 37. In this form of the invention, it is contemplated that the brackets 31, sockets 34 and tubes 36 shall be formed of metal, while the rods 37 shall be formed of wood. However, any desirable material may be employed for the several parts, such as plastic, metal, hard rubber or the like and the invention is not limited to any particular material. It is contemplated that the rods 37 shall engage throughout the length of the tubes 36 and that the pivot pins 35 shall pass therethrough as a means to prevent acci-

dental displacement of the rods. Latch means are employed to maintain the support rods 37 in either the extended angular position or in the inner vertical position, consisting of detents 38, struck from the side of the sockets 34, for frictional engagement in a suitable recess formed in the side of each tube 36. Thus the support will be maintained in either position against accidental shifting.

10 While the lower marginal edge of the net has been shown as tightly drawn around the lower part of the pen by the draw string 26, it will be apparent, that the net may be formed with each lower corner split, and provided with tie tapes, 15 so that the lower marginal edges of the net may be drawn under the bottom edge of the pen and tied behind each leg, thus serving to prevent a child from shoving articles between the lower edge of the net and the bottom of the pen. The 20 lower marginal edge of the net may also be provided with clips or other fastening devices intermediate the corners of the pen that would serve to secure its edge along the bottom of the pen.

It will be apparent from the foregoing that a 25 very novel and highly desirable catch net and supporting means therefor has been provided for children's play pens. The net and associated elements are cheap to manufacture and are easily attached or removed and will result in a considerable saving in the cost of broken bottles or 30 the like, thrown or rolling from the pen and is highly effective for the purposes for which it was designed.

It is to be understood, that the invention is 35 not limited to the precise construction and arrangement shown, but that it includes within its purview, whatever changes fairly come within either the terms or the spirit of the appended claims.

40 Having described my invention, what I claim as new and desire to secure by Letters Patent is:

1. A catch net for use with children's play pens having corner legs, said net consisting of a net extending entirely around the play pen and normally arranged at an angle to the bottom and extending upwardly and outwardly from the sides of said pen, brackets detachably secured at each lower corner of the pen, support rods carried by the brackets for the support and positioning of the net with respect to the pen, pivotal means between the brackets and support rods whereby the support rods are shiftable inwardly for positioning the net against the pen and latch means carried by the brackets and support rods for maintaining the rods in a predetermined position of adjustment.

2. A catch net for use with children's play pens having corner legs, said net comprises a mesh net extending entirely around the pen, brackets secured to the lower corners of the pen, support rods pivotally carried by the brackets to swing outwardly from each corner leg, latch means carried by the brackets and rods for retaining the rods in angular adjustment outwardly of the sides of the play pen, means carried by the outer ends of the rods for the support of the net, the net having an upper marginal edge provided with an elastic band, the lower edge of the net provided with a draw string whereby the lower marginal edge of the net is maintained in snug engagement with the pen.

3. A catch net for use with children's play pens that have corner legs, said net includes an open mesh net extending entirely around the pen, angle brackets detachably secured to the legs

75

adjacent the bottom of the pen, a support rod pivotally connected to each angle bracket to swing toward and from the pen, the net being suspended from and positioned around the rods whereby the rods determine the angularity of the net with respect to the pen, the rods extending outwardly at an angle from the corners of the pen to provide an identical net area on each side of the pen, the net having an elastic band connected entirely around its upper marginal edge, the net having a draw string extending entirely around its lower marginal edge, the brackets and support rods having latch means therebetween whereby the rods may be positively positioned at an angle from the pen to maintain the net angularly disposed from the pen, the latch means also serving to dispose the rods in parallelism with the pen to dispose the net against the pen, the latch means being operable from the outer terminus of the support rods.

4. A catch net for use with a play pen of the type that is generally square in top plan and that is equipped with corner legs and a bottom, said net adapted to be disposed entirely around the pen with its upper marginal edge arranged spaced from the pen and its lower marginal edge snugly engaging the sides of the pen in close proximity to the bottom, angle brackets detachably secured to each leg of the pen adjacent the bottom, net supporting rods pivotally connected with each bracket to swing in a vertical plane toward and away from the legs, latch means between the brackets and the rods whereby the rods may be positively positioned in the outer and inner positions, the net being arranged to extend around the rods with the rods supporting the net at angles outwardly from the sides of the pen throughout its circumference, the upper marginal edge of the net provided with an elastic band to maintain the net taut from rod to rod entirely around the pen, means to secure the upper marginal edge of the net adjacent the upper end of each rod, the lower marginal edge of the net provided with a draw string whereby such edge may be drawn into snug engagement with the

sides of the pen adjacent the bottom of the pen and into overlying relation to the brackets, the said latch means permitting the net to be collapsed to a position against the sides of the pen.

5. The structure as recited in claim 4, wherein the brackets are secured to the legs by conformable straps having a clamping screw.

6. The structure as recited in claim 4, wherein the angle brackets are provided with a forwardly projecting U-shaped socket having its forward end wall inclined outwardly, a tubular socket member that is pivotally supported in the U-shaped socket to swing toward and from the play pen and limited in its outward swinging movement by the inclined end wall, a net supporting and positioning rod engaging in the tubular socket, pivotal means passing through the U-shaped socket, the tubular member and the rod, detents pressed inwardly from the sides of the U-shaped socket for engagement with the tubular member whereby the tubular member and its supported supporting rod are retained in an adjusted position.
